LAWRENCE S. SCHMIDT, OF PITTSBURGH, PENNSYLVANIA, ASSIGNOR TO SCHMIDT-McCORMICK COMPANY, OF PITTSBURGH, PENNSYLVANIA, A CORPORATION OF PENNSYLVANIA.

SAFETY MEANS FOR FURNACE-COOLING STRUCTURES.

1,276,420.

Specification of Letters Patent. Patented Aug. 20, 1918.

Application filed November 9, 1915. Serial No. 60,533.

To all whom it may concern:

Be it known that I, LAWRENCE S. SCHMIDT, a citizen of the United States, residing at Pittsburgh, in the county of Allegheny and State of Pennsylvania, have invented certain new and useful Improvements in Safety Means for Furnace-Cooling Structures, of which the following is a specification.

- 10 This invention relates to improvements in furnace cooling structures and particularly to means for insuring the supply of cooling fluid to such structures upon failure of the normal supply.
- 15 While the invention is applicable for various uses, it is particularly adapted for use in connection with devices employed for the protection of the gas ports of regenerative furnaces, a point where it is especially desirable that failure of fluid supply shall not be had and that the normal circulation of the water through the devices shall be maintained.

20 Devices for such cooling purposes, of course, have their greatest efficiency when the normal fluid circulation is continuous. When such continuity is materially varied or broken, as by the failure of the supply of fluid or material decrease in the fluid pressure, the temperature conditions of the structure protected by the devices change materially, resulting in damage to a more or less extent to the structure.

25 The present invention has for its principal object the reduction or elimination of bad effects due to changes in circulation conditions, this being accomplished by automatically bringing into action an auxiliary supply of fluid which tends to maintain the circulation and thereby reduces the variation in temperature conditions of the structure being protected.

30 To these and other ends, my invention consists in the improved construction and combination of parts hereinafter fully described, illustrated in the accompanying drawings, and more particularly pointed out in the appended claims.

35 In the accompanying drawings, Figure 1 is a vertical sectional view of a portion of a regenerative furnace, the section being taken on a line intersecting a gas port.

Fig. 2 is a detail view of connections employed in the safety mechanism.

Fig. 3 is a diagrammatic view of a portion of a furnace showing a special form of cooling structure.

In Fig. 1 of the drawings, 10 designates the gas port of a regenerative furnace, 11 the air port, and 12 the refractory mass structure in proximity to these ports.

13 designates a port cooling structure, shown in this instance as D-shape in contour and positioned to encircle the gas port, 60 the cooling structure being provided with a fluid inlet 14 connected to a source of supply (not shown), a valve 14^a controlling the inflow of the fluid, the connections to the structure being shown as leading through an arch 12^a in the mass structure. The outlet for the cooling structure is indicated at 15, located substantially at the top of the structure, the pipe connection therefrom, indicated at 15^a, leading outwardly and then upwardly to discharge into the top of a tank 16, hereinafter referred to as the auxiliary fluid supply. 17 indicates a valve-controlled auxiliary pipe connection leading from the cooling structure.

25 The cooling structure disclosed is such as to provide a continuous circulation channel therein for the cooling fluid entering at inlet 14 and discharging at outlet 15, the structure being comparatively narrow and therefore having a comparatively small cross sectional area. This provides for a somewhat rapid circulation of the fluid therein, which fluid is discharged into tank 16 when valve 14^a is open, pipe connection 17 being normally closed. As shown in Fig. 3, a plurality of these structures is employed, each having its individual supply and discharge in the manner indicated.

30 It is to be understood, however, that while I prefer to employ this particular type of cooling structure, I do not limit the invention to such type, the safety mechanism to be described being well adapted for use in connection with various other types of such structures, where the cooling action is provided by the circulation of a cooling fluid.

35 In such structures, normal supply of the fluid and proper operating of the cooling structure provides the desired protection which the structure is designed to afford.

2
 However, in cases where the fluid pressure becomes materially reduced or fails entirely, the temperature conditions of the structure being protected become materially changed 5 through the change in the normal circulation through the cooling structure.

To remedy this condition I provide means for connecting the inlet for the cooling structure with the tank 16, and control this 10 connection in such manner that under normal supply operation, the mechanism remains inactive, but when material reduction in fluid pressure or an entire failure of fluid supply takes place, this connection becomes 15 automatically active to provide supply and thus tend to maintain the normal circulation within the cooling structure.

This means is in the form of a pipe connection 17 having a check valve 18, the 20 upper end of said pipe 17 being open to the tank 16 while the lower end of said connection 17 is connected to the supply inlet pipe between valve 14^a and the cooling structure. I also provide a check valve 19 25 in the supply pipe between valve 14^a and the point of connection of pipe 17 with the supply pipe.

Check valve 18 opens automatically in a 30 direction to permit flow of fluid from tank 16, while check valve 19 automatically opens in the direction to permit entrance of fluid from the main supply.

By this arrangement it will be understood that under normal pressure conditions in 35 the supply and with valve 14^a open, check valve 19 will remain open, thus placing the supply in open communication with the cooling structure; it also places pipe connection 17 in open communication with the 40 main supply, but since the pressure from the main supply predominates that from tank 16, especially since check valve 18 is located adjacent to tank 16, check valve 18 will remain closed, thus preventing a discharge 45 of fluid from pipe 17 into tank 16, or from the tank to pipe connection 17, the amount of fluid in tank 16 being controlled in suitable manner as by an overflow pipe 16^a. Should, however, the pressure from the supply 50 become materially reduced or an entire failure ensue, this predominance of pressure of the main supply will be eliminated, the result being that check valve 18 will open and check valve 19 close, thus shutting off 55 the main supply and opening up the auxiliary supply from tank 16, the fluid from which then passes into the inlet 14 and into the circulation system. Since the fluid within the cooling structure becomes heated and expands therein, the circulation will be substantially maintained, the fluid passing out 60 through the normal discharge, this expansion action of the fluid being sufficient to overcome the small difference in height between the discharge outlet and the level 65 of the fluid in tank 16. This action will

continue until the pressure of the main supply again becomes sufficient to open check valve 19 against the pressure from tank 16, whereupon, the normal operation will again 70 take place, check valve 18 again closing through the predominance of main supply pressure.

In the form of Fig. 3, the cooling structure comprises a plurality of individual units 75 13^a each having an independent fluid circulating system, and adapted to discharge into a common receptacle, auxiliary pipe connections (not shown) being provided as 80 in the form of Fig. 1.

As will be readily understood, the arrangement is such as to produce a pressure column inactive in the circulation system when the normal supply pressure is of greater value than that of the column, in 85 which case, the valve 18 is closed and valve 19 is retained open by the greater pressure of the main or normal supply. When, however, the pressure of the main supply becomes of less value than that provided by 90 the height of column, the latter becomes active, closing the valve 19 and permitting valve 18 to open under the slight head of fluid within the receptacle. In this manner, the pressure of the column does not 95 materially fall below the pressure provided by the height of the column, so that assurance is had of a definite minimum pressure in the system regardless of the reduction in the main supply ahead of valve 19. 100 As valve 18 is located close to receptacle 16, the slight head of fluid will not be effective until the pressure value of the column exceeds that of the main supply.

What I claim is:—

1. The combination with a furnace cooling structure having a normal cooling fluid circulation and supply, of means rendered active by the failure of the normal supply for maintaining the circulation of fluid 110 through the cooling structure.

2. The combination with a furnace cooling structure having a normal cooling fluid circulation and supply, of means rendered active by the failure of the normal supply 115 for maintaining the circulation of fluid through the cooling structure, said means being rendered inactive by restoration of normal supply conditions.

3. The combination with a furnace cooling structure having a normal fluid circulation and supply, of auxiliary supply means including an automatically operable valve, the activity of the auxiliary means being controlled by the fluid pressure of the normal supply.

4. The combination with a furnace cooling structure, of means for providing a circulation of cooling fluid through said structure, said means including normal and aux- 125

- iliary fluid supplies, and means whereby the activity of the auxiliary supply is controlled by pressure variations of the normal supply.
5. The combination with a furnace cooling structure, of means for providing a circulation of cooling fluid through said structure, said means including a normal supply, a receptacle for receiving the circulation discharge, and connections between said receptacle and the normal supply for delivering the discharge-fluid to the entrance of the circulation system, means to control said delivery by pressure variations of the normal supply, said receptacle acting as an auxiliary fluid supply.
6. The combination with a furnace cooling structure, of means for providing a circulation of cooling fluid through said structure, said means including a normal supply, a receptacle for receiving the circulation discharge, and connections between said receptacle and the normal supply for delivering the discharge-fluid to the entrance of the circulation system, whereby said receptacle may act as an auxiliary fluid supply, said connections having an automatically operable valve for controlling the activity of the receptacle as such supply.
7. The combination with a furnace cooling structure, of means for providing a circulation of cooling fluid through said structure, said means including a normal supply, a receptacle for receiving the circulation discharge, and connections between said receptacle and the normal supply for delivering the discharge-fluid to the entrance of the circulation system, whereby said receptacle may act as an auxiliary fluid supply, said connections having a valve for controlling the activity of the receptacle as such supply, said valve being controlled by the pressure variations of the normal supply.
8. The combination with a furnace cooling structure, of means for providing a circulation of cooling fluid through said structure, said means including a normal supply, a receptacle for receiving the circulation discharge, and connections between said receptacle and the normal supply for delivering the discharge-fluid to the entrance of the circulation system, whereby said receptacle may act as an auxiliary fluid supply, said connections having an automatically operable valve for controlling the activity of the receptacle as such supply, and an automatically operable valve in the normal supply and subject to the pressure variations thereof, said valves coöperating to control the activity of the auxiliary supply.
9. The combination with a furnace cooling structure, of means for providing a circulation of cooling fluid through said structure, said means including a normal supply, a valve in said supply, a receptacle for receiving the circulation discharge, and a fluid

conduit connected to the fluid supply between said valve and the cooling structure and leading to said receptacle, said conduit having a valve for controlling the passage of fluid from said receptacle, said valves being controlled by the pressure variations in the normal supply.

10. The combination with a furnace cooling structure, of means for providing a circulation of cooling fluid through said structure, said means including a normal supply, a valve in said supply, a receptacle for receiving the circulation discharge, and a fluid conduit connected to the fluid supply between said valve and the cooling structure and leading to said receptacle, said conduit having a valve for controlling the passage of fluid from said receptacle, said latter valve being positioned adjacent said receptacle and adapted to be maintained in closed position when the normal supply pressure exceeds the pressure of the column of fluid between said valves, said conduit valve automatically opening when the normal supply pressure becomes less than that of the fluid column.

11. The combination with a furnace cooling structure, of means for providing a circulation of cooling fluid through said structure, said means including a normal supply, a valve in said supply, a receptacle for receiving the circulation discharge, and a fluid conduit connected to the fluid supply between said valve and the cooling structure and leading to said receptacle, said conduit having a valve for controlling the passage of fluid from said receptacle, said latter valve being positioned adjacent said receptacle and adapted to be maintained in closed position when the normal supply pressure exceeds the pressure of the column of fluid between said valves, said conduit valve automatically opening when the normal supply pressure becomes less than that of the fluid column, the closing movements of one valve being concurrent with the opening movements of the other valve.

12. The combination with a furnace cooling structure, of means for providing a circulation of cooling fluid through said structure, said means including a normal supply, a check valve in said supply opening in the direction of fluid flow from the main supply, a receptacle located on a plane above the plane of the cooling structure for receiving the circulation discharge, and a vertically extending fluid conduit connected to the main fluid supply between said valve and the cooling structure and leading to said receptacle, said conduit having a check valve opening in the direction of fluid flow from said receptacle, said check valves coöperating to provide a pressure column of definite value, said column maintaining the conduit valve closed when the normal supply pres-

sure exceeds the value of the column pressure.

13. The combination with a furnace port, of a cooling structure therefor comprising a plurality of individual units each having an independent fluid circulation system including a fluid supply, a receptacle adapted to receive the circulation discharge of the several systems, and automatically operable 10 valved means connecting said receptacle to each system for rendering the fluid of said receptacle active in the circulation system of either unit upon material reduction in fluid pressure of the normal supply for such unit.

14. The combination with a furnace port, of a cooling structure therefor comprising a plurality of individual units each having an independent fluid circulation system including a fluid supply, a receptacle adapted 20 to receive the circulation discharge of the several systems, and automatically operable valved means connecting said receptacle to each system for rendering the fluid of said receptacle active in the circulation system 25

of either unit upon material reduction in fluid pressure of the normal supply for such unit, said means including a pressure column of definite value for each system adapted to determine the period of activity 30 of the receptacle fluid.

15. The combination with a furnace cooling structure having a normal cooling fluid circulation and supply, a receptacle adapted to receive the circulation discharge, and 35 automatically operable valved means connecting said receptacle to the circulation system for rendering the fluid of said receptacle active in such system upon material reduction in fluid pressure of the normal supply for said system, said means including a pressure column of definite value adapted to determine the period of activity 40 of the receptacle fluid.

In testimony whereof, I affix my signature 45
in presence of two witnesses.
